Attorney

UNITED STATES PATENT OFFICE.

JOSEPH HORYDCZAK, OF NEWARK, NEW JERSEY.

SHOE FORMER.

Application filed October 10, 1924. Serial No. 742,835.

This invention relates to shoe formers and particularly to those shoe formers which are expandible in the forward part of the shoe.

5 The primary object of my invention is the provision of an improved shoe former.

Another object of my invention is the provision of a shoe former having an expandible means operating both to the right and to 10 the left from the longitudinal axis of the former.

Another and further object of my invention is the provision of a shoe former comprising an expanding means having a combined sliding and pivoted movement.

Another and still further object of my invention is the provision of an improved shoe former having an expandible means for complementary portions at the forward end 20 thereof, the expandible means comprising superimposed plates pivoted together and to the respective complementary portions and having converging slots therein, the slots being under the influence of a longitudinally movable member for causing the expansion of the complementary portions.

Another and still further object of my invention is the provision of a shoe former comprising an expanding means having a plurality of leverages, at 30 respective parts of the expanding operation.

Other and further objects will be apparent, to those skilled in the art, from a reading of the complete specification.

35 Referring to the drawing wherein I have illustrated a preferred embodiment of my invention,

Fig. 1 is a plan view of the operating mechanism of my invention, showing the parts contracted.

Fig. 2 is a plan view similar to Fig. 1, but showing the parts expanded.

Fig. 3 is a side elevational view.

Fig. 4 is a detail cross sectional view on the line 4-4 of Fig. 2.

The same reference characters refer to the same or similar parts throughout the several views.

50 The numerals 10, 10^a, designate the forward complementary portions of the shoe former which act, when expanded, to preserve the shoe in its proper shape. At 11 is the heel portion of the former for engaging the inner rear portion of the shoe 55 when the former is in place.

The complementary portions are slotted

on their inner sides to permit entry of the plates 12, there being one for each complementary portion. These plates 12 are of tapered shape and each has an extending 60 portion 13 in which is located the pivot bearing for pivots 14 which may be in the form of nails driven into the complementary portions as shown. It is to be noted that there is a space at each side of the extending portions. This permits of a pivotal movement of the plates 12 in their respective slots for a purpose to be described.

In the plates 12 are slots 15 which overlap each other and are loosely pivoted together by the pivot member 16. These slots 15 are preferably arranged substantially at right angles to the axis of the shoe former as a whole.

Arranged at an angle to the axis of the 75 shoe former are slots 17 which are connected to a longitudinally movable member 18 by pins 19 which loosely slide in the slots 17. It will be noted that the slots 17 are placed so that they occupy a sharp angle relative to 80 each other. Since when the longitudinally movable member 18 moves, the pins 19 maintain their relation to each other, it follows that the plates 12 will be forced apart or drawn together, depending upon which direction the longitudinally movable member 85 is moved relative to the complementary portions.

Pivotedly connected to the longitudinally movable member at 20 is a toggle member 21 90 which has at its other end a thumb piece 22 which latter is used to operate the toggle. Adjacent the thumb piece 22 is a pivot member 23 which passes through the toggle member 21 and also through the other toggle member 24, the slide 25 and the spring 26, the latter being held in the slide 25 as shown in Fig. 3. The pivot member 23 is provided with an extended portion at the outer end of which is the button 24'. That portion of the 100 pivot member 23 which is normally held in the plane of the toggle member 24 by the spring 26, is cylindrical in cross section while the portion normally in the plane of the toggle member 21 is flattened as shown in 105 Fig. 4.

The toggle member 24 is provided with a series of pivot bearings 27, shown in Fig. 3. These pivot bearings 27 are connected together by slots 28 to provide for passage of 110 the flattened portion of the pivot member 23 already described. That portion of the

slide 25 remote from the pivot member 23, is freely movable along the toggle member 24. When it is desired to give a different length over-all to the shoe former, the button 24 is 5 pressed in against the spring 26 which forces the cylindrical portion of the pivot member out of the pivot bearing 27 which brings the flattened portion in line for registration with the slots 28. The toggle 24 may now be 10 readily forced in either direction. When the proper length is reached, the pivot member 23 is released. The spring 26 will force it to place in the first pivot bearing with which it registers.

15 In using my shoe former, the toggle is placed in angular position and the shoe former inserted in the shoe. The thumb piece is then pressed downwardly to extend the toggle. This action, of course, forces 20 the forward toggle member 21 in a forward direction with a consequent driving forward of the longitudinally movable member 18.

Considering now Fig. 1, it may be noted 25 that the pins 19 are to the rear of the pivots 14. For this reason the pressure on the members 12 will be to the rear of the pins 14. As a point is approached where the pressure will pass directly into the pivots 14, the plates 12 will turn on their pivots 14. 30 At this point, the leverage, forcing the complementary portions 10, 10^a away from each other, pivots the plates 12, swinging them to positions shown in Fig. 2. During this 35 swinging movement of the plate 12, the pivot pin 19 follows a curved path relatively to the pins 14 until the plates 12 rest at the bottoms of their respective slots as shown in Fig. 2. A continued forward movement of the longitudinally movable member is carried out. During this movement, the angle, 40 between the slots 17 of the respective plates 12, because of the change of position of the plates 12, is lessened, thus permitting a greater movement of the longitudinally movable member for a given outward movement 45 of the complementary members 10, 10^a. The pressure outwardly by these complementary members will consequently be greater during this latter part of the stroke. This is, of 50 course, what is desired.

It is clear that to release the toggle and the complementary members, it is only necessary to lift the thumb member 22.

What I have shown and described an embodiment of my invention in detail, I desire 55 to have it understood that the showing is merely illustrative and that modifications and changes may be made without departing from the spirit of my invention and within 60 the scope of the appended claims.

Having described my invention, what I claim is:—

1. A shoe former comprising complementary portions of a shape to fit the forward 65 end of a shoe, a heel engaging member, ex-

panding means between the complementary portions, and connecting means between the heel engaging member and the expanding means for operating the latter, the expanding means including slotted plates pivoted 70 respectively to the complementary portions, for maintaining the complementary portions at equidistance from the connecting means during the expanding operation a portion of the slot of each plate being forward of the 75 pivot point.

2. A shoe former comprising complementary portions of a shape to fit the forward end of a shoe, and expanding means between the complementary portions, the expanding means including two members pivoted respectively to the complementary portions and being relatively bodily movable, the pivoted members each having a slot, the slots converging toward each other in a forward 85 direction, and a longitudinally movable member having means slidably engaging the slots.

3. A shoe former comprising complementary portions of a shape to fit the forward 90 end of a shoe, and expanding means between the complementary portions, the expanding means including two members pivoted respectively to the complementary portions, the pivoted members each 95 having a slot, a portion of which is forward of the pivot of the pivoted member and another portion of which is in the rear thereof, the slots converging toward each other in a forward direction, and a longitudinally movable member having means 100 slidably engaging the slots.

4. A shoe former comprising complementary portions of a shape to fit the forward 105 end of a shoe, and expanding means between the complementary portions, the expanding means including two members pivoted respectively to the complementary portions and having a limited pivotal movement relatively thereto, the pivoted members each having 110 a slot, a portion of which is forward of the pivot of the pivoted member and another portion of which is in the rear thereof, the slots converging toward each other in a forward direction, and a longitudinally movable member having means 115 slidably engaging the slots.

5. A shoe former comprising complementary portions of a shape to fit the forward end 120 of a shoe, expanding means between the complementary portions, the expanding means including two members pivoted respectively to the complementary portions and having a limited pivotal movement relatively thereto, the pivoted members each having a slot, a portion of which is forward of the pivot of the pivoted member and another portion of which is in the rear thereof, the slots converging toward each other in a forward 125 direction, a longitudinally movable member 130

having means slidably engaging the slots, a heel engaging member and a pushing means between the heel engaging member and the longitudinally movable member.

6. A shoe former comprising complementary portions of a shape to fit the forward end of a shoe, expanding means between the complementary members, and a longitudinally movable member cooperating with the expanding means and having a connection therewith, the expanding means including a portion to guide the connection in a substantially straight line during the first part of the stroke and in a curved line during a later portion of the stroke.

7. A shoe former comprising complementary portions of a shape to fit the forward end of a shoe, expanding means between the complementary members, and a longitudinally movable member cooperating with the expanding means and having a connection therewith, the expanding means including a portion to guide the connection in a substantially straight line, relative to one of the complementary portions, during the first part

of the stroke, in a curved line during a later portion of the stroke and in a substantially straight line during the last part of the stroke but in a different direction.

8. A shoe former comprising complementary portions of a shape to fit the forward end of a shoe, a heel engaging member, an expanding means for the complementary portions, a toggle mechanism connecting the heel engaging member and the expanding means, one of the toggle members having a single pivot bearing for connection to another toggle member, this other toggle member having a plurality of pivot bearings for selective connection to the first toggle member, a pivot for securing the toggle members in pivotal relation, a guide on the second toggle member and connected to the pivot, means for causing the release of the pivot to vary the adjustment by connection to another pivot bearing and a spring for holding the pivot in place.

In testimony whereof I hereunto affix my signature.

JOSEPH HORYDCZAK.
